UNITED STATES PATENT OFFICE

MICHAEL W. RANKE, OF HUDSON FALLS, NEW YORK

APPARATUS FOR COLORING PAPER STOCK

Application filed January 28, 1929. Serial No. 335,651.

This invention relates to paper manufacture and has for its object the provision of a simple apparatus by the use of which paper stock may be impregnated throughout its volume with coloring matter and a uniform shade or tint appear in the finished product. The invention provides means whereby as the paper stock is pumped from the storage chest to be delivered to the forming elements of the paper-making machinery it will receive coloring material and will be so treated that the color will be uniformly distributed throughout the mass. Apparatus embodying the invention is illustrated in the accompanying drawings, and the invention resides in certain novel features which will be hereinafter first fully described and then more particularly defined in the appended claims.

In the drawings:

Figure 1 is a view in perspective showing means for practicing the invention in a somewhat diagrammatic manner,

Fig. 2 is an enlarged transverse section showing one form of agitator, and

Fig. 3 is a vertical section showing another form of agitator.

In the drawings, the reference numeral 1 indicates a head box receiving paper stock from a storage chest through a conduit 2 which leads into the bottom of the box and has communication with a pump (not shown) whereby the stock will be delivered into the head box under a sufficient pressure to attain the desired circulation. Within the head box are partitions 3 and 4 dividing the interior of the box into three compartments, the stock delivery pipe 2 leading into the central compartment. The partition 4 is provided centrally with an opening or cut-out portion 5 through which the surplus stock may overflow into the end compartment and then return by gravity to the storage chest through the conduit 6 leading from the bottom of said compartment. The partition 3 has an opening 7 therethrough at its center and this opening

is covered or uncovered by manipulation of a gate 8 slidably mounted in ways 9 at the sides of the opening and adapted to be supported in a set position in any convenient manner. From the compartment defined between the partition 3 and the adjacent end of the head box, the paper stock flows through a conduit 10 to the forming elements of the paper-making machinery.

Disposed at any convenient point in the workroom is a series of tanks or reservoirs 11 which may be of any desired capacity and are intended to hold a supply of coloring matter. Between the reservoirs or tanks 11 and the head box are intermediate tanks 12 which are supported in a somewhat elevated position, as by a frame 13, and from the tanks 12 pipes 14 lead into that compartment of the head box from which the stock passes to the forming machine. The pipes 14 are equipped with cutoff valves 15 whereby the flow may be regulated and from each tank 12 an overflow pipe 16 leads to the reservoirs or storage tanks 11. These overflow pipes 16, in actual practice, will be equipped with nipples or other swiveled outlets whereby the overflow may be directed into any one of the reservoirs. Communicating with the interior of the several reservoirs adjacent the bottoms thereof are outlet pipes 17 which are each equipped with a cutoff valve 18, and these pipes communicate with the inlet of a pump 19 of any approved construction, a motor 20 being connected with each pump and being illustrated in a conventional manner. The outlet of each pump 19 communicates through a pipe 21 with one of the tanks 12, as shown.

Within that compartment of the head box into which the coloring matter is delivered through the pipes 14 is an agitator which, as shown in Figs. 1 and 2, consists of end disks 22 connected by longitudinal slats or spaced bars 23 whereby an open cylinder is formed. The disks 22 are rigidly secured to a shaft 24 which is journaled in the sides of the

head box and has one end projected through the wall of the box and equipped with a pulley 25. A driving belt 26 is trained around the pulley 25 and operatively connects the same with the driving shaft of a small motor 27. The head box is provided with a washout valve 28 in the bottom of the color-receiving compartment so that the compartment may be thoroughly cleaned and all residue driven out whenever deemed desirable. White water is supplied to the color-receiving compartment through a pipe 29 which is disposed adjacent the head box and delivers thereinto in any approved manner, this pipe being equipped with a cutoff valve, indicated at 30.

With the apparatus shown in Fig. 1, two different coloring ingredients may be delivered into the agitator compartment and the finished stock will, therefore, have a color or tint which is a blend of the two colors delivered to the compartment. For instance, if it be desired to have a green color in the finished paper, yellow coloring matter may be delivered through one pipe 14 and blue coloring through the other pipe 14, and the depth or shade of green which is to be attained will be determined by regulating the cutoff valves 15 so as to permit a greater or less flow of either of the color supplies. White water is supplied simultaneously to the agitator compartment in a desired quantity to maintain the liquid condition of the paper stock and the agitator is constantly rotated so that the stock will be thoroughly stirred and the coloring liquids will be caused to penetrate the entire body of the stock and to mingle therewith and with each other so that a uniform color or shade will be found in the finished product. Of course, the apparatus may be extended so as to provide for a mingling of more than two color ingredients and any desired tint may be thus obtained.

In Fig. 3, I have illustrated a variation in the structure of the apparatus, in which the head box is indicated by the reference numeral 31 and the agitator compartment by the numeral 32. In this form of the invention, the agitator is not mounted directly in the compartment 32 but is housed within a cylindrical well 33 below the compartment and in direct communication therewith through the bottom of the same. A pipe 34 leads from the well to the forming elements and an agitator shaft 35 is disposed vertically within the well and the compartment 32, being journaled in bearings of any convenient form provided within the well and at the top of the compartment as is obvious. At the lower extremity of the shaft 35, a suction fan 36 is secured thereon and above the fan an agitator 37 is secured to the shaft, the agitator consisting essentially of annularly spaced vertical beater bars, preferably having their upper ends curved forward in the direction of rotation to avoid throwing the stock up out of

the well when operating at high speed. The coloring matter is supplied to the compartment 32 through a pipe 38 corresponding in all respects to the pipe 14 and at the upper end of the shaft 35 is provided beveled gearing 39 driven from a motor 40 so as to rotate the agitator. This form of the invention operates in all essential respects in the same manner as the first described form but accelerates the flow of the stock to the drying elements through the use of the suction fan.

In both illustrated forms of the invention, the apparatus is very simple and compact and is not apt to get out of order. The tanks 12 receive the coloring material under pressure, and from these tanks said material flows by gravity so that, while the desired flow to the agitator compartment is attained, the coloring material is not delivered to the stock with such head that it is apt to impair the quality of the stock or overflow from the compartment, the rate of flow being nicely regulated through adjustment of the valves 15 so that the coloring matter supplied will bear a constant ratio to the volume of stock supplied.

It will be understood that by this apparatus any desired tint or shade may be obtained and maintained through the run with uniformity, the mixing being accomplished as the color is impregnated in the stock. There is no necessity for mixing a large batch of color before starting the paper machine, and there will be no errors in matching color runs.

Having thus described the invention, I claim:

1. Apparatus for coloring paper stock comprising a head box, partitions subdividing the box into receiving, overflow and mixing compartments, the partition separating the receiving and overflow compartments having an opening to maintain a predetermined level of the paper stock in the receiving compartment, and the partition separating the receiving and mixing compartments having a gate controlled opening for regulating the delivery of stock from the receiving to the mixing compartments, a series of color-containing reservoirs, distributing tanks intermediate the said reservoirs and head box and disposed wholly above the plane of the latter to supply the coloring matter to the mixing chamber by gravity, valved pipes between the distributing tanks and mixing chamber, overflow pipes between the distributing tanks and reservoirs, means for drawing the coloring matter from the reservoirs and supplying it in regulated quantities to the distributing tanks, an agitator in the mixing compartment, and conduits connected with the several compartments.

2. Apparatus for coloring paper stock comprising a head box including a mixing compartment, a well depending therefrom and having a delivery pipe leading from the bottom thereof, a vertical shaft mounted in the

well and mixing compartment, a suction fan in the bottom of the well secured to the said shaft, and an agitator in the well above the suction fan secured to said shaft and comprising annularly spaced vertical bars having their upper ends curved forwardly to supplement the action of the fan and prevent upward movement of the stock.

5 In testimony whereof I affix my signature.
